APPARATUS FOR PRODUCING ARTIFICIAL RESPIRATION

Bo Carl Henrik Sahlin, Lund, Sweden

Application September 22, 1934, Serial No. 745,111
In Sweden September 27, 1933

8 Claims. (Cl. 128—30)

This invention relates to apparatus for producing artificial respiration of that type in which a casing is used adapted to enclose a part of the body of the patient but to leave uncovered the head, neck, limbs and the anal- and urogenital-parts. In the said casing rhythmical changes of pressure are effected, so that the chest and abdomen of the patient are compressed and expanded alternately.

10 Apparatus of the said type generally have been comparatively complicated and consequently expensive but nevertheless usable only for persons of special limited sizes and besides the application of the apparatus was troublesome and time-consuming. Besides, the anal- and urogenital-parts often were accessible only with difficulty, which, regarding patients, who must be treated for a long period, involved great inconveniences. Finally, sufficient regard has not been paid to the fact, that different positions of the patient during the treatment often are desired.

20 All the said disadvantages are removed through the present invention which relates to an apparatus which chiefly is characterized by a support for the back of the patient and a hood substantially in the shape of a reversed U or the like which by means of its shanks can straddle the said support and fit tightly to the same and which is provided with tightening cloths or the like fitting to the body and the support.

25 Preferably, the said support is adjustable with regard to its width, so that it may be adapted to different sizes of body. Also the width of the hood is hereby adapted to different sizes of the bodies and besides there will always be a certain space between the sides of the body and the hood, which is of importance in order that the movements of the body resulting from the respiration may not be prevented in any way during the treatment.

30 The invention also comprises some details, which are stated in the following description of a form of execution of the apparatus shown as an example in the accompanying drawings.

35 Fig. 1 is a side view of the apparatus; a patient resting on his back is illustrated by dotted lines. Fig. 2 is an end view of the apparatus partially in cross section on the line II—II in Fig. 1; some parts are shown in unsymmetrical positions. Fig. 3 shows in an end view and, on a greater scale, some details. Fig. 4 is a side view and Fig. 5 a plan view of the same details. Fig. 6 is a section of some other details. Fig. 7 is a section on the line VII—VII of Fig. 6. Fig. 8 shows in end view a further detail. Fig. 9 shows,

in a side view, a driving unit. Fig. 10 is an end view of the same unit. In Figs. 9 and 10 a casing enclosing the unit is shown in section so that inner parts are visible. Fig. 11 shows a detail of the driving unit.

5 The apparatus is carried by a pillar 1, to which a support 3 is pivoted at 2. The said support carries a frame work 4 which is swingable on the horizontal shaft 5 of the support but is normally held in adjusted position by a locking mechanism 10 which may be disengaged by means of a handle 7. The frame work is turned or tilted laterally on the pin 2 by rotating a crank 8 on the shaft 5. For that purpose shaft 5 is screw-threaded so that the rotating of the shaft 5 in the one 15 or the other direction results in the shaft being moved toward the right or left hand side through a die 10 journaled in the pillar 1 (Fig. 2), which evidently, effects a tilting of frame work 4 laterally of pillar 1. A plate 11, adapted to 20 support the legs of the patient, is swingably connected to the frame work 4. A second plate 12 is swingably connected to the frame work and adapted to serve as a support for the head of the patient. The said plates 11 and 12 are fixed in adjusted position by easily manipulated locking mechanisms 13 and 14 respectively. Preferably, the plate 11 is provided with an adjustable purchase 111 for the feet of the patient, which purchase partially supports the patient 25 when the table 11 has been brought into a certain slanting position.

30 Two slides 15 and 16 (Fig. 2) are provided in the top part of the frame work, which slides may be moved toward and from each other transversely of the apparatus and are adapted to form a mounting for a rest or support for the back of the patient. The said support together with the plates 11 and 12 constitute an equivalence to an adjustable table for operations.

35 Preferably, the said support consists of airtight rubber-cloth stretched over two longitudinal supporting rods 18 of a comparatively soft material. The said rods are fixed in a suitable manner in the slides 15 and 16, which are constructed as frames or the like and are movable in guides 19 (Figs. 3-5) provided in the frame work 4. Ropes 20 or the like are fixed to the longitudinal edges of the rubber-cloth and pass round rollers 21 (Figs. 3 and 8) back to the frame work 4 to 40 which they are fixed in any suitable manner.

45 End pieces 22 (Fig. 3) or the like are fixed to the slides 15 and 16 and provided with screw-threaded dies 23 engaged by screw-threaded shafts 24. The said shafts are journaled in 50

55

the frame-work 4 and provided with right handed screw-threads for the dies 23 of the one slide and left-handed screw-threads for the dies of the other slide. Sprocket wheels 25 are fixed on the shafts 24 and a chain 26 is placed round the sprocket wheels so that while one of the shafts is rotated this results in the second shaft also being positively rotated. The rotating may be effected by the crank 8 mentioned above, which for this purpose is dismounted from the shaft 5 and mounted on one of the shafts 24 at the one or the other side of the table. As the shafts are rotated in the one or the other direction the said dies, evidently, are moved either toward or from each other on the said shafts, provided with right-handed and left-handed threads, which results in the slides 15 and 16 being moved towards or from each other. During this movement the rubber-cloth 17 always is held in a stretched condition owing to the provision of the ropes 20.

The rest or support constituted by the cloth 17 and the rods 18 is straddled by a reversed substantially U-shaped hood. Preferably the said hood is made of springy sheet metal 27, to the edges of which are fixed, in a suitable manner, tightening cloths 28. The shanks of the hood, which extend through the slides, are adapted to be forced tightly against the cloth 17 at those places where it is placed round the supporting rods 18. For the said forcing of the shanks against the cloth 17, bell crank levers 29 or the like are used which are mounted in a turnable and in a slidable manner on rods 30 carried by the slides 15 and 16 (Fig. 8). The said levers 29 are connected by a girdle 31 which is laid over the hood and may be tightened partly for forcing the shanks of the hood downwards, partly for turning the levers 29, so that their inner arms are caused to force the shanks of the hood against the rods 18. As already stated, the levers 29 are slidably mounted on the rods 30. This is of importance with regard to the proper mounting of the hood longitudinally of the table. The said girdle 31 may be suitably guided relatively to the hood.

For causing the tightening cloths 28 to fit closely to the body of the patient as well as to the rubber-cloth 17, jam-members (Figs. 3-7) are provided, which according to the illustrated form of execution consist of tongue shaped pieces 33 or the like provided with a handle 32. The said jam-members are carried by blocks 34, which are slidably mounted on the rods 30 mentioned above. Blocks 34 are provided with openings for the shanks of a recurved pin 35, the one shank of which extends through a slot 36 in the jam-member 33. A nut 37 is in screw-threaded engagement with the shank just mentioned and a die 38 is located under the nut. A handle 39 is pivoted to the said die 38 and bears against the jam-member 33 by means of an eccentric 40 or the like. Jam-member 33 rests upon a clutch member 41 guided by the slot 36 and provided with teeth 42, adapted to engage corresponding teeth provided in the block 34. A spring 43 is located between the clutch member and the block which spring tends to disengage the teeth. The curve shaped part of the pin embraces a rod 44, which is parallel to the rod 30.

As the described jam-devices should be used handle 39 is swung upwards into a vertical position, so that the eccentric 40 is rotated and the spring 43 moves the clutch member 41 upwards,

the engagement of the teeth being thereby interrupted. The jamming engagement of the pin with the rod 44 is also reduced in some degree. Block 34 may now be moved along the rod 30 so that the jam-member 33 is adjusted into a suitable position. The jam-member is then swung by means of the handle 32 inwards against the tightening cloth 28 substantially in the manner shown in Figs. 3 and 5, so that it is forced inwards against the body of the patient and the tightening cloth fits closely to same and partially to the rubber-cloth 17. Handle 39 is then swung downwards into the horizontal position, so that the jam-member is forced downwards and the tightening operation is completed. The teeth of the clutch members now again engage each other and the curve shaped part of the pin 35 is forced against the rod 44 while the jam-member and the block 34 are locked in adjusted position. For the disengaging of the members a single manipulation is sufficient, consisting in the handle 39 being swung upwards into the vertical position. The jamming operation is performed in substantially the same simple manner and involves besides the advantage that the jamming positions may be adapted with regard to size of the body of the patient and to other different conditions.

After the patient has been placed on the table with his back resting on the same and the members of the table have been brought into the desired positions one makes certain that the supporting rods 18 are located somewhat outside the sides of the patient, which easily is effected by rotating one of the shafts 24 in the one or other direction by means of the crank 8 so that the slides 15 and 16 are moved towards or from each other. The U-shaped hood is then placed in proper position over the sheet and the abdomen of the patient, so that it straddles with its shanks the patient as well as the support. It must be observed, that there will be a certain distance between the sides of the patient and the shanks of the hood, so that the chest of the patient may freely expand in all directions without being prevented in any way from such movements as correspond to the maximum breathing movements. The gaining of the said distance is rendered possible by the support being adjustable, so that the rods 18 to which the shanks of the hood are jammed always may be adjusted into such positions that they are located outside the sides of the patient. As the hood has been placed substantially in the desired position the girdle 31 is tightened which results as before stated in the hood being somewhat lowered and the bell crank levers 29 forcing the shanks of the hood inwards against the supporting rods 18, so that the shanks fit closely to the cloth 17 placed on the said rods. The jam-devices 33-43 described above are then pushed on the rods 30 and 44 into suitable positions and the jam-members 33 are swung inwards against the tightening cloths 28 in the manner described above, so that the cloths fit closely to the body of the patient, whereupon the jam-members are locked. The treatment may then commence and is effected substantially in known manner by changes of the pressure in the interior of the hood being produced. The said changes of the pressure are transmitted through a hose 45 connected to the hood (Fig. 1).

For effecting the changes of pressure preferably a separate, easily movable unit is used. Figs. 9 and 10 show a form of execution of the

same. The said unit comprises a casing 50, which is movable on wheels and in which are mounted an electric motor 51 and a pump 52 with piston. The said motor which is controlled outside the 5 casing by means of a hand wheel 53, rotates by means of worm gear 54 a fly wheel 55 which is connected to the piston 57 of the said pump by a rod 56. For the altering of the stroke of the 10 piston a slot 58 is provided in the fly-wheel 55, in which the connecting pin of the said rod 56 may be locked in adjusted position. The pump cylinder 52 communicates through a pipe 59 and the hose 45 mentioned above with the hood to which, consequently, rhythmical changes of pressure 15 are transmitted as a result of the motion of the piston 52. A branch 60 of the pipe 59 may be put into a controllable communication with the atmospheric air by a cock 61 or the like, so that a rapid and convenient controlling 20 of the changes of pressure in the hood is rendered possible. As a guard against the creation of non-permissible variations of the pressure, the pump cylinder may be provided with two valves 62, one of which is opened for the admission 25 of air into the cylinder if a too great vacuum is created in the same and the other valve is opened for the discharging of air from the cylinder if a too high pressure should arise. Only 30 one of the valves is shown in the drawings. For the indicating of the changes of the pressure in the interior of the hood a manometer preferably is provided which through a separate conduit communicates directly with the interior of the hood. The separate conduit may be connected 35 to the hood simultaneously with the hose 45.

Owing to the fact that the pump sometimes must operate during very long periods an effective lubricating of the same is of importance. For that purpose a ring-shaped chamber 63 is provided in the lower part of the pump cylinder, which chamber is partially charged with a lubricant, into which lubricant a ring-shaped flange 64 of the piston 57 is dipped at each descending movement. The piston is thereby lubricated automatically and, besides, lubricant is dragged upward and passes downwards to the bearing of the connecting rod for instance through substantially radial grooves or channels. For preventing lubricant from splashing outward at the 50 lower end of the cylinder, as the flange 64 of the piston is dipped into the lubricant, special protection means are provided.

Although the hood straddling the rest or support and the adjustability of the rest with regard to its width render possible a convenient adjusting of the apparatus to different sizes of the bodies within comparatively wide limits, two hoods of different sizes at least preferably are used. Besides, the hood may be composed of 60 parts which may be moved toward and from each other, so that the dimensions of the hood may be altered.

A certain leakage even of a slight amount at the different joints of the hood may scarcely be obviated, but practically it may be neglected. The leakage on the other hand effects a certain draught which cools the patient and for the obviating of this drawback the air delivered by the pump may be heated in a suitable manner.

70 The construction of the apparatus may, evidently, be varied without exceeding the limits of the invention which consequently is not confined to comprise the described form of execution. For instance all setting mechanism may 75 be combined with or coupled to a controlling de-

vice common to the same, which renders possible the substantially simultaneously setting at all tightening places. The said controlling mechanism may, if desired, be connected also with the supporting rods. Any other suitable device 5 than the piston pump may be used for effecting the changes of the pressure and so on.

I claim:

1. In an apparatus for producing artificial respiration with the aid of a casing which is 10 adapted to enclose a part of the body of the patient but to leave uncovered the head, neck, limbs and the anal- and urogenital-parts and in the interior of which rhythmical changes of the pressure are effected, for instance by means of a 15 pump, the combination of a support for the back of the patient, which support is adjustable with respect to its width, a substantially U-shaped hood, which by means of resilient shanks can straddle the said support and fit tightly to the 20 same, independent of the adjusted width of the support, cloths adapted to fit closely to the body and to the said support and slides carrying the support and consisting of frames which are 25 provided with jam devices, by means of which the shanks of the hood may be jammed to the support.

2. In an apparatus for producing artificial respiration with aid of a casing, which is adapted 30 to enclose a part of the body of the patient but to leave uncovered the head, neck, limbs and the anal- and urogenital-parts and in the interior of which rhythmical changes of the pressure are effected, for instance by means of a pump, the combination of a support for the back of the patient, which support is adjustable with respect to its width and consists of a rubber-cloth, which is stretched over two supporting rods, extending longitudinally of the apparatus and mounted on two slides which are slidable toward and from 40 each other transversely of the table of the apparatus, a substantially U-shaped hood, which by means of resilient shanks can straddle the said support and fit tightly to the same, independent 45 of the adjusted width of the support and tightening cloths adapted to fit closely to the body and to the said support.

3. In an apparatus for producing artificial respiration with the aid of a casing, which is adapted 50 to enclose a part of the body of the patient but to leave uncovered the head, neck, limbs and the anal- and urogenital-parts and in the interior of which rhythmical changes of the pressure are effected, for instance by means of a pump, the combination of a support for the back of the patient, which support is adjustable with respect to its width and consists of a rubber-cloth, to each longitudinal edge of which is fixed one end of a rope which returns over a roller carried by 55 a slide, said rope being fixed at its other end to the table of the apparatus so that the cloth always may be held in stretched condition, independently of the width of the support, a substantially U-shaped hood which by means of resilient shanks can straddle the said support and fit tightly to the same, independent of the adjusted width of the support, and tightening cloths 60 adapted to fit closely to the body and to the said support.

4. An apparatus as claimed in claim 1, characterized by the fact, that the jam-devices are adjustable longitudinally of the table, so that they may be mounted into suitable positions with relation to the hood mounted in proper position. 75

5. An apparatus as claimed in claim 1, characterized by the fact that the jam-devices comprise eccentrics, which are rotatably mounted on rods carried by the slides and may be connected 5 to one another by means of a girdle placed over the hood so that by stretching the girdle the hood is moved downwards and the eccentrics are forced against the shanks of the hood causing the same to fit closely to the support.
- 10 6. An apparatus as claimed in claim 1, characterized by the fact that the slides in addition to the jam-devices are provided with jam-members which are movable longitudinally of the table and adjustable and lockable for jamming 15 the tightening cloths of the hood against the support, the tightening cloths being thereby forced against the body of the patient and caused to tighten to the body of the patient.
7. An apparatus as claimed in claim 1, characterized by the fact that with the slides motion transmitting means are combined, which may be acted upon at both sides of the table, so that the adjusting of the width of the support may be effected at any side of the table. 5
8. An apparatus as claimed in claim 1, characterized by the fact that the motion transmitting devices of the slides consist of screw-spindles which are journaled in the table of the 10 apparatus and provided with right-handed and left-handed screw-threads and screwed into corresponding dies fixed to the slides respectively so that the slides are moved towards each other, as the spindles are rotated in one direction and 15 away from each other as the spindles are rotated in the opposite direction.

BO CARL HENRIK SAHLIN.
